MERCURY SWITCH RELAY

Charles H. Cartwright and Carl H. Larson, Elkhart, Ind., assignors to The Adlake Company, a corporation of Illinois

Application April 14, 1938, Serial No. 202,003

5 Claims. (Cl. 200—97)

This invention relates broadly to mercury switches, for certain features or parts of it can be used to advantage with almost any type of mercury switch. But more specifically, the invention pertains to that type of mercury switch in which spaced electrodes, together with a quantity of mercury and a magnetically responsive displacer, are hermetically sealed within a glass envelope, after which the switch is associated with a coil which controls the movement of the displacer within the envelope to change the mercury level and thereby cause the electrical circuit between the spaced electrodes to be closed or opened according to the particular construction of the switch.

In general the objects of the invention are to provide a time delay switch which, by slight changes in physical structure and/or apportionment of parts during fabrication, can be made to fulfill widely varying performance specifications; one which is relatively cheap to manufacture, particularly because it can be easily tested for its actual time delay characteristics before the parts are hermetically sealed within the switch envelope; and one which is reliable in performance over long periods of time.

These are but a few of the objects and advantages of the switch which will hereinafter be described, reference being had to the accompanying drawings in which

Fig. 1 is a perspective view showing a novel and preferred mounting for the switch;

Fig. 2 is a vertical sectional view taken on the line 2—2 of Fig. 1, the switch, however, being shown in elevation;

Fig. 3 is a plan view of the switch with its mounting;

Fig. 4 is an enlarged vertical sectional view of a back contact switch embodying some of the principles of this invention, the switch parts being shown in their normal position of rest when the associated relay coil is deenergized;

Fig. 5 is a view showing the relationship of the switch parts at the instant when the displacer is raised by the associated coil;

Fig. 6 is a horizontal sectional view taken on the line 6—6 of Fig. 5;

Fig. 7 is a side elevational view of the time delay cup;

Fig. 8 is a vertical sectional view of a front contact switch embodying some of the principles of this invention, the switch parts being shown in the position which they take at the instant when the associated coil is deenergized and the dis-

placer rises, because of its buoyancy, to the top of the switch envelope;

Fig. 9 illustrates the manner in which the time delay cup is instantly filled whenever the displacer is lowered by the action of the coil;

Fig. 10 is a horizontal sectional view taken on the line 10—10 of Fig. 8; and

Fig. 11 shows a modified form of the invention in which the switch parts are constructed and arranged so that there is a relatively short time interval when the circuit through the switch is being closed and a relatively long time interval when the circuit through the switch is being opened.

Certain preferred forms of the invention have been chosen for illustration and description, in compliance with Section 4888 of the Revised Statutes, and the appended claims should be construed as broadly as the prior art will permit.

The switch mounting

The switch mounting shown in Figs. 1 to 3 is a simple and inexpensive construction which not only provides an efficient iron circuit for the magnetic flux, but also affords physical protection for the switch.

The mounting for the switch, generally designated 20, comprises an L-shaped plate 21 connecting top and bottom pole plates 22 and 23, respectively, the latter having a downwardly extending flange 24 by which the relay may be mounted on the wall by screws 25. The switch-operating coil 26 is telescoped over the switch 20 and over top and bottom pole sleeves 27 and 28, which are rigidly secured to the top and bottom pole plates 22, 23, respectively. The plates 22 and 23 are removably secured to the L-shaped plate 21 by screws 29, so that the switch may be readily inserted in the coil 26 and assembled with the associated iron circuit, and when so assembled the bottom of the switch is supported on the horizontal flange 30 of the plate 21, and the top of the switch is slightly below the top of the sleeve 27, so that it is amply protected from accidental blows.

Preferably the iron circuit is made of cold rolled steel, annealed, or any high grade soft iron.

Back contact switch (slow make, slow break)

The switch shown in Figs. 4—7 inclusive is a quick make, slow break, back contact switch, comprising a switch envelope 31 (preferably of 733A glass), through the base of which molybdenum electrodes 32, 33, are pinch-sealed. The

5 electrode 32 is surrounded by a glass insulating sleeve 34 to a point 35, where it is fused with a short sleeve 36, of refractory tubing, preferably made of ceramic material such as Alundum RA84, or RA360, inasmuch as this material is readily fusible with Corning 733A glass. The end of the electrode 32 is bare, leaving a contact portion 37 which extends a substantial distance above the top of the sleeve 36, and is adapted to be intermittently placed in electrical contact with the mercury fill 41 of the switch.

10 The electrode 33 is surrounded by a glass sleeve 38 until it enters the time delay cup, generally designated 39, and the bared end of the electrode 15 33 forms a contact 40 which is constantly immersed in the mercury within the cup 39.

15 The time delay cup 39 consists of an elongated ceramic tube 42 (preferably made from Alundum RA84 or RA360), the base of which is fused to a 20 glass enlargement or bead 43 associated with the electrodes 32, 33. The cup 39 is telescoped over both of the contacts 37, 40, and at some point below the contact 37; the side wall of the cup is reduced in thickness, as indicated at 44, by 25 means of a grinding wheel or file, and through this thinned portion of the cup wall a small mercury passage 45 is provided which constitutes the timing element for the switch.

30 The mercury fill is adapted to be raised and lowered between high and low levels by means of a magnetically responsive displacer 46, the top of which is slightly above the lower pole sleeve 28 when the coil 26 is deenergized. Springs 47, 48, are secured to the top and bottom, respectively, of the displacer 46 to cushion the movement of the displacer within the envelope, and to clamp guide washers 49 in place on the displacer. The upper portion of the displacer is enlarged to provide greater mass for the displacer, but the interior of the displacer is in free 40 communication with the space on the outside of the displacer through an opening 50, so that the gas fill of the envelope, which preferably includes both helium and hydrogen, can readily pass 45 through the top of the displacer without impedance.

45 The switch parts in Fig. 4 are shown in the position which they take when the coil 26 is deenergized, and it should be noted that the level 50 of the mercury, when the displacer is in its lower position (the high mercury level), is above the lower edge 51 of the cup 39. The upper margin of the cup is inclined, so that when mercury is displaced to close the circuit through 55 the electrodes 32 and 33, the mercury can enter the cup on the side adjacent to the low point 51, while the gas in the cup will escape along the opposite side of the cup. Obviously when the cup 39 is filled with mercury the circuit through 60 the contacts 37 and 40 is closed.

65 When the displacer 46 is raised to the position shown in Fig. 5, the mercury level on the outside of the cup 39 falls immediately to a position slightly above the passage 45, but the column of mercury within the cup 39 recedes gradually as mercury passes slowly through the restricted passageway 45 into the main body of mercury. As soon as the mercury level within the cup falls 70 below the top of the ceramic sleeve 36, the circuit through the contacts 37 and 40 is broken.

75 Subsequent deenergization of the coil 26 will result in the displacer falling to the position in which it is shown in Fig. 4, and the immediate displacement of mercury by the displacer will cause the cup 39 to become instantaneously

flooded with mercury, with the result that the circuit through the contacts 37 and 40 is made within a few hundredths of a second after the coil is deenergized.

Front contact switch (quick make, slow break)

The front contact switch shown in Figs. 3-10 inclusive differs but slightly from the back contact switch of Figs. 4-7 inclusive, the principal difference being that the time delay cup 39 of the 10 front contact switch is positioned somewhat higher within the envelope and the displacer 52 is of lighter construction. To the extent that the switch parts are the same, or substantially alike, no description is necessary, and these parts 15 are indicated by like numbers on the drawings.

The displacer 52 comprises an outer sleeve 53 of magnetic material, interiorly fitted with a refractory sleeve 54, preferably of glass or ceramic material, which projects from both ends of the 20 sleeve 53. The two sleeves are held in desired relative position by the top and bottom springs 47, 48, which are tightly fitted over the projecting ends of the sleeve 54, as clearly shown in 25 the drawings.

The air gap 55 between the top and bottom pole pieces 27, 28, is somewhat lower than the air gap in the back contact switch of Figs. 4-7 inclusive, and when the coil 26 is energized the displacer is pulled down to the bottom of the 30 switch envelope, as shown in Fig. 9 to immediately flood the cup 39 with mercury and substantially instantaneously establish the electrical circuit between the electrodes 32, 33. Upon deenergization of the coil 26, the displacer rises by 35 its buoyancy to the position in which it is shown in Fig. 8, and the mercury level outside of the cup 39 immediately drops to the level in which it is shown in Fig. 8. As the mercury gradually escapes from the cup 39 through the opening 45, 40 the mercury level within the cup 39 recedes until it falls below the edge 56 of a ceramic cup 57 associated with the contact 37, and as the mercury passes the edge 56 the circuit through 45 the contacts 37 and 40 is broken. The time which it takes for the mercury to recede from the top of the time delay cup 39 to the edge 56 of the electrode cup 57 represents the time delay factor 50 of the switch. When the mercury has leveled off with the displacer in raised position it is at its 55 low level, as indicated by the line 58.

Front or back contact switch (slow make and slow break)

60 It is apparent that by very slight modifications 55 the back and front contact switches shown in Figs. 4-10 inclusive can be easily changed into slow make, slow break switches, i. e., switches in which the time delay action of the restricted mercury passage 45 is utilized on making the circuit through the electrodes, as well as when breaking that circuit. This may be accomplished merely by using a smaller quantity of mercury in the switch, so that when the displacer 46 of the back contact switch and the displacer 52 of the front contact switch are lowered to the positions in which they are shown in Figs. 4 and 9, respectively, the mercury fill fails to rise above the edge 51 of the cup 39, although it must rise 65 above the top of the sleeve 36 (Fig. 4) and above the edge 56 of the electrode cup 57 (Fig. 8). By this arrangement the only way mercury is permitted to enter the cup 39 is through the restricted opening 45, and the distance between 70 the low level of the mercury (i. e., the level of 75

the mercury when the displacer is in its raised position and the mercury is at rest, as indicated by the lines 58 in Figs. 5 and 8), and the lowermost effective point on the contact 37 (the top 5 of the sleeve 36 in Fig. 4, and the edge 56 of the cup 57 in Fig. 8), determines the time delay characteristics of the switch for the making of the circuit.

Since the high mercury level, indicated by the 10 line 59 in Figs. 5 and 8, in a slow make, slow break switch of this type (as well as the slightly higher mercury level which is reached at the instant the displacer is lowered) is above the top of the sleeve 36 and the edge 56 of the electrode 15 cup 57, the breaking of the circuit through the electrodes will be delayed by the retarded drop of the mercury column within the time delay cup 39. In some cases it may be desirable to 20 increase the height of the cup 39 in order to make certain that mercury will not overflow the top of the cup and destroy the timing action of the restricted mercury passage 45 when closing the circuit between the electrodes 32 and 33.

25 *Front or back contact switch with retarded make and slow break*

In Fig. 11 there is shown a switch which has a relatively short time delay when the circuit is being closed, and a relatively long time delay 30 when the circuit is being opened. By way of example, the switch may have a six second time delay when making the circuit, and a three minute time delay when breaking the circuit, and this particular relationship of time delays is extremely difficult to obtain in switches of this type.

The switch shown in Fig. 11 is of the front contact type, but it is obvious that the principles of the switch could easily be incorporated 40 in a back contact switch. To the extent that the switch corresponds with the front contact switch in Figs. 8-10 inclusive, the description will not be repeated, and like reference characters are used on the drawing. The principal difference 45 between the two switches is that a gas impervious thimble 60, preferably of glass, is sealed to the electrodes 32, 33, in place of the cup 39, and the thimble is provided in its top wall with a mercury valve, generally designated 61, comprising a porous seat 62, preferably of coarse 50 ceramic material, such as Alundum, grade RA98, an a telescoping sleeve 63 of relatively dense ceramic material, such as Alundum, grade RA84. The sleeve 63 and seat 62 are fused into the top 55 wall of the thimble to form a mercury valve cup, and the parts of the switch are so proportioned that when the displacer 52 is lowered the mercury rises above the top of the thimble 60 a sufficient distance to make certain that a quantity 60 of mercury 64 is in the valve cup 61. The lower portion of the thimble 60 is provided with a restricted mercury passage 45, which retards the flow of mercury between the interior and exterior of the thimble.

65 When the switch parts are in the position in which they are shown in Fig. 11, with the mercury at its low level, the circuit through the electrodes is open. Upon lowering the displacer 52 by the action of the coil 26 (or by deener- 70 gizing the coil in the case of a back contact switch), the mercury level on the outside of the thimble immediately rises to a level indicated by the line 65, which preferably is above the edge 66 of the sleeve 63 to insure that the mercury 75 valve cup 61 will be filled with mercury. The

mercury within the thimble 60 gradually rises as mercury is permitted to flow into the thimble through the restricted passageway 45, and as soon as the level reaches the edge 56 of the cup 57 the circuit through the electrodes 32, 33, will be closed. The time for the mercury to reach this height depends, of course, upon the size of the opening 45, the diameter of the thimble 60, and certain other factors. The gas entrapped within the thimble 60 does not in any way retard the movement of mercury to circuit closing position, because the seat 62 is sufficiently porous to readily pass the gas through the seat and through the mercury globule 64 in the cup 63 without creating any substantial back pressure. 10 15

When the mercury in the switch has leveled off to its normal high level 67, due to the displacement of the gas in the thimble 60 with mercury, the thimble 60 is completely filled with mercury and subsequent deenergization of the coil, which 20 causes the displacer 52 to rise to its uppermost position, as shown in Figs. 8 and 11, has the result of lowering the outside mercury level to the position indicated by the line 68; but the mercury within the thimble 60 is restrained in its 25 downward movement by the slow passage of gas through the dense porous sleeve 63 and seat 62, the mercury 64 in the valve 61 preventing gas from passing through the seat 62 into the thimble 60 without first traversing the dense time 30 delay sleeve 63. The time that it takes for the mercury to fall from the top of the mercury chamber in the thimble 60 to the edge 56 of the electrode cup 57 constitutes the time delay 35 interval which characterizes the breaking of the circuit, and this interval is dependent for its value on the density of the sleeve 63, the diameter and thickness of the walls of that sleeve, the diameter of the thimble 60, the difference in height between the top of the mercury chamber 40 in the thimble 60 and the edge 56 of the mercury cup, and various other factors. It is not difficult with this arrangement to obtain time delays of several minutes on the breaking of the circuit through the electrodes of the switch. 45

It should be noted that the restricted mercury passage 45 does not interfere with the timing action of the sleeve 63, because the gas-time delay element is much slower in its action than the mercury leakage element. 50

55 *Summary of advantages*

The switch structures which have been described have certain inherent advantages, and these will be mentioned briefly.

1. It is obvious that the time intervals for making and breaking the electrical circuits can be varied between wide limits by properly choosing appropriate dimensions for the time delay cup 39 and the mercury orifice 45, and by properly 60 positioning the intermittently immersed contact within the cup 39.

2. Since the functioning of the time delay element is not dependent upon gas densities (with the exception of the modified form shown in Fig. 11), the switch can be readily tested during fabrication for its actual time delay values with the assurance that the same time delay values will obtain when the switch is hermetically sealed off at the top, as indicated at 69. For example, 65 it is known that an .027 drill will give a six second time delay for a switch of given dimensions. Much time and labor is saved in this way and the switch can be produced with a corresponding saving in cost. 70 75

3. Making the time delay cup 38 of ceramic material and placing the mercury orifice below the low mercury level in a relatively thin wall of the cup greatly increases the accuracy of the time delay functions of the switch, since the short passage through the side wall of the cup is too small to house a bubble which might interfere with the smooth flow of mercury between the interior and exterior of the cup, and any bubble which finds its way into the opening will immediately disappear because the pressure of mercury on both sides of the opening forces the gas through the surrounding porous wall of the ceramic cup 38.

4. Although it is not essential in all cases to have the opening 48 below the low mercury level, for extreme accuracy it is preferred because the error introduced by the erratic effect of surface tension is avoided.

5. The extended contact 37 in Figs. 4-10 inclusive serves a dual function. Although it is impossible to determine for a certainty that the exceptionally quick and clean closing of the circuit through the electrodes 32 and 33 (clean in the sense that oscillograph records show that there is no chatter when the circuit is closed) is obtained in a particular way, it seemed probable that the explanation for this desirable action is that the mercury, in spilling over the edge of the cup 42, first strikes the contact 37, thereby immediately closing the circuit through the electrodes, and the continued rush of mercury into the cup prevents any separation of the mercury column from the contact which could produce a chatter. In addition the extended contact 37 decreases the contact resistance of the switch when the circuit is closed.

6. It has been found by extensive tests that the time for closing the circuit is decreased and made more uniform when the top of the cup 38 is slanted, as shown in the drawings, presumably because the mercury tends to enter the cup on the low side and the gas tends to escape from the high side.

7. By having both of the contacts 37 and 48 within the cup 38, the direct path of the electrical circuit between the contacts 37 and 48 excludes the restricted mercury passage 45, thus giving the switch a higher current carrying capacity.

8. A switch of the type disclosed can be used very successfully on structures which are subjected to much jostling or vibration, as, for example, automobiles, buses, railway cars, and the like.

We claim as our invention:

1. In a mercury switch adapted to produce a relatively short time delay when the circuit through the switch is being closed and a relatively long time delay when the circuit is being opened, said switch comprising a switch envelope, a mercury fill, a gas fill, electrodes in the envelope, one of which has a contact adapted to be intermittently placed in electrical contact with the mercury fill, a thimble telescoped over said contact and providing a mercury and gas chamber which is closed except for a restricted mercury passage below the level of the contact and a restricted gas passage above the level of the contact, and means for bypassing the restricted gas passage when gas is being permitted to escape from the chamber.

2. In a mercury switch adapted to produce a relatively short time delay when the circuit through the switch is being closed and a relatively long time delay when the circuit is being

opened, said switch comprising a switch envelope, a mercury fill, a gas fill, electrodes in the envelope one of which has a contact adapted to be intermittently placed in electrical contact with the mercury fill, a thimble telescoped over said contact and providing a mercury and gas chamber which is closed except for a restricted mercury passage below the level of the contact and a restricted gas passage above the level of the contact, means for raising and lowering the mercury fill between high and low levels, and a mercury valve associated with the thimble and permitting gas to freely escape from the thimble but preventing gas from entering the thimble without passing through the restricted gas passage, whereby the restricted mercury passage times the flow of mercury within the thimble to circuit closing position and the restricted gas passage times the flow of mercury within the thimble to circuit opening position.

3. In a mercury switch, a switch envelope, a mercury fill, electrodes having contacts within the envelope one of said contacts being above the low mercury level, a time delay cup telescoped over said contact and having a mercury metering orifice below the level of that contact, and means carried by the cup above said contact to restrict the passage of gas, and a magnetically responsive displacer to shift the mercury fill above both contacts, the mercury metering orifice being at all times immersed in the mercury fill.

4. In a mercury switch relay having prescribed operating characteristics, the combination of a relay coil, a switch associated with the coil, said switch comprising an envelope, spaced electrodes in the envelope, a mercury fill, a hollow displacer responsive to the coil for shifting the mercury level, and cooperating time delay elements associated with one of said electrodes to delay the movement of mercury with relation to said electrode upon a change in the condition of the electrical circuit through the coil, one of said time delay elements comprising a gas leakage device fixed with respect to one of said electrodes and the other comprising a mercury cup provided with a restricted wall opening for the timed passage of mercury, the gas leakage time delay element associated with said electrode being relatively slow in its action as compared to the mercury passage time delay element associated with the cup.

5. In a mercury switch relay having prescribed operating characteristics, the combination of a relay coil, a switch associated with the coil, said switch comprising an envelope, spaced electrodes in the envelope, a mercury fill, a hollow displacer responsive to the coil for shifting the mercury level, and cooperating time delay elements associated with one of said electrodes to delay the movement of mercury with relation to said electrode upon a change in the condition of the electrical circuit through the coil, one of said time delay elements comprising a gas leakage device fixed with respect to one of said electrodes and arranged to control the movement of mercury in one direction with respect to said electrode and the other one of said time delay elements comprising a mercury cup provided with a restricted wall opening for the timed passage of mercury arranged to control the movement of mercury in the other direction with respect to said electrode, whereby the switch is characterized by a delayed make and a delayed break of the circuit through the electrodes.

CHARLES H. CARTWRIGHT.
